(57) **CLAIM**

The ornamental design for a elliptical cross sectional ring member for a ring mechanism, as shown and described.

DESCRIPTION

FIG. 1 is a perspective view of the elliptical cross sectional ring member for a ring mechanism;

FIG. 2 is a front elevation view thereof, with the rear elevation view being a mirror image of;

FIG. 3 is a right side elevation view thereof, with the left side elevation view being a mirror image of;

FIG. 4 is a top plan view thereof;

FIG. 5 is a bottom plan view thereof;

FIG. 6 is a cross section of the elliptical cross sectional ring member for a ring mechanism taken from the 6-6 line on FIG. 4; and,

FIG. 7 is a cross section of the elliptical cross sectional ring member for a ring mechanism taken from the 7-7 line on FIG. 4.

Features illustrated in broken lines form no part of the claimed design.
